INCLINED HINGE

Earl E. Howe, Royal Oak, Mich.

Application January 9, 1939, Serial No. 249,866

4 Claims. (Cl. 16—135)

This invention relates to a concealed door hinge particularly adapted for swingably supporting a door from a curved wall, as for example, the support of an entrance door of an automobile which is curved in direction normal to swinging movements and further, in conjunction with walls which are inclined as in the case of an automobile body having upwardly converging side walls.

In my co-pending application Serial No. 200,907 filed April 2, 1938, I have disclosed and claimed a hinge suitable for use in automobile bodies and this invention has objects similar, in many respects, to my previous invention. The principal objects are to provide a sturdy, reliable hinge of the concealed type which is susceptible to easy alignment for properly fitting the door to its frame, which will withstand severe uses such as door slamming, closing of the door by pushing against one corner and the imposition of undue weight as may be caused by a child riding thereon, and which also is economical to manufacture.

In an automobile body having upwardly converging side walls the door frame is, of course, inclined with the result that assembly of a hinge therein ordinarily disposes the hinge pin at an angle to the vertical. The angularity of the hinge pin is such that any point on the door swings through an arc which is inclined to the horizontal and inasmuch as the angle is such that gravity will cause the door to swing to its closed position, the angularity of the hinge pin is termed the tumble-in angle. The excessive tumble-in angle present in conjunction with the inclined walls of the later automobile body designs is undesirable in the respect that the door closes too rapidly and unless held may strike a person entering the automobile or who has completed his entrance except as to his foot and ankle. From the standpoint of appearance it is undesirable that the arc of swinging movement of the door should depart too great a degree from a horizontal plane. Accordingly, it is an important object of this invention to provide a concealed hinge which permits the door to swing substantially parallel to the ground, or in a substantially horizontal arc even in the presence of an extreme tumble-in angle.

Another object of the invention is to provide a concealed hinge for supporting an automobile door in such manner that gravity biases closing movement thereof. This feature is particularly desirable in conjunction with the left hand doors of an automobile in order that such doors will not remain open while the automobile is parked

on a highway, as such doors in an open position constitute a hazard to traffic on the highway.

Another object is to provide a concealed hinge for supporting a curved door for swinging movement about an axis which is disposed externally 5 of the automobile body at both the top and the bottom of the door frame, and which passes through the body between the top and bottom of the frame. The purpose of the hinge in this respect is to avoid the necessity of comparatively 10 long, outwardly projecting hinge elements, such as are ordinarily used in conjunction with curved doors. This is made possible by use of a single hinge, disposed within the plane of the body wall, and whose axis of pivotal movement if prolonged 15 passes the top and bottom of the door frame externally thereof.

Another object is to provide a hinge of the character above mentioned embodying means facilitating vertical and lateral adjustment of 20 the door, means susceptible to bending for providing angular adjustment of the door and which offers no interference with the glass run.

Other objects and advantages will become more fully apparent as reference is had to the 25 accompanying drawing wherein my invention is illustrated, and in which:

Fig. 1 is a side elevation of an automobile having doors hung with the present hinge,

Figs. 2 and 3 are sections taken respectively on the lines 2—2 and 3—3 of Fig. 1,

Fig. 4 is a perspective view of the hinge,

Fig. 5 is a perspective view of the hinge illustrating the use of dual hinge pins, and,

Fig. 6 is a section illustrating a modification of 35 the hinge construction.

More particularly, 1 indicates an automobile body having side walls of curved section and which converge upwardly. A plurality of doors are hung in door openings in the body, the hinge 40 assembly in each case being identical as far as the principle of operation is concerned. The hinge for the right front door is interchangeable with the hinge of the left rear door, and the hinge of the left front door is interchangeable 45 with the hinge of the rear right door. The hinge for supporting the right front door 2 is described hereinafter by way of example.

A hinge member 3 is secured to the door pillar 4 at or near the trim line 5, preferably immediately below, and a second hinge member 6 is pivotally attached to the hinge member 3 by a pin 7. The second hinge member 6 is attached to the edge of the door 2 which is curved to correspond to the curvature of the body 1, and in- 55

clined generally to correspond to the converging condition of the body side walls.

The hinge is of the concealed type, which is to say it is not visible either from the interior or from the exterior of the vehicle when the door is closed. In appearance, the hinge is somewhat larger than a conventional automobile hinge and resembles two joined aligned hinges in some respects. These are, however, very essential differences.

The hinge member 3 is composed of a flat or plate-like main portion having a plurality of holes 8 therethrough for the reception of screws 9 which extend through over-size openings 10 in the pillar 4 and engage screwthreaded openings in a floating anchoring plate 11. Along one edge of the main portion 3 are widely separated cylindrical pintle receiving portions 12 and a relatively long cylindrical pintle receiving portion 13, all of which preferably are formed from the same piece of stock as the plate portion 3. The axes of the three cylinders 12 and 13 are aligned.

The other hinge member 6 is generally of U-shape in endwise view, with the branch 14 disposed at an angle greater than 90° relative to the plate portion 6. The branch 17 is integrally united with the branch 14 and extends substantially perpendicular thereto with its upper edge 18 spaced a greater distance from the plate portion 6 than is the lower edge 19.

There are two coplanar spaced branches 14 and two coplanar spaced branches 17, the spacing in both cases being approximately equal to or slightly greater than the length of the cylindrical portion 13. Each branch 17 terminates in cylindrical pintle receiving portions 20 spaced for interfitting with the cylindrical pintle receiving portions 12 and 13, and the plate portion 6 has holes 21 therethrough receiving fastening elements 22 for securing the hinge to the door 2.

As may be seen in Fig. 2 the axis A of the hinge pintle is inclined to the vertical, it being disposed whereby it extends inwardly of the vehicle body as it extends upwardly. As viewed in Fig. 45 1, the axis A is inclined forwardly as it extends upwardly, whereas the plate portion 6, to which the door is attached is substantially vertical. The result of this compound angularity of the axis A is that the door 2 when swung about the axis 50 50 A travels in a substantially horizontal arc. The arc is not truly horizontal, however, for it is desired that it will be disposed at a slight angle to the horizontal in order that gravity tends to bias closing movement of the door.

55 In the hinge above described a single hinge pin 7 is used. Fig. 5 illustrates, however, that the cylindrical pintle receiving cylinder 13 may be dispensed with in some cases, and two separate hinge pins 7a used instead of a single pin.

60 In the modified form illustrated in Fig. 6 the hinge member 3a is attached permanently to the door pillar 4a prior to attachment of the door to the hinge. The hinge portion 6a is attached to the inner side edge of the door 2a by bolts 65 65 9a which extend through oversize apertures 10a and engage screwthreaded apertures in a floating anchoring plate 11a. The oversize apertures 10a permit vertical and longitudinal adjustments and transverse adjustments are provided for by 70 the use of shims 25.

The modified hinge is identical to the hinge above described with the exception of the shape of the branch portions, which instead of being generally of U-shape are altered in shape to permit attachment to the side of the door rather

than to the edge. It includes a pair of branches 14a united with the plate portion 6a and a second pair of branches 17a which engages the hinge pin, the branch portion 14a being adapted to swing in the mouth of a recess formed in the pillar 4a to receive the hinge plate 3a. A cover plate 26 is secured to the edge of the pillar 4a to close the mouth of the recess with the exception of that part necessary to permit swinging movement of the branches 14a. The plate 26 is 10 provided for the sake of a pleasing appearance, and also to prevent as much as possible the insertion of anything which might interfere with operation of the hinge.

Fig. 6 also discloses the use of rubber cushioning means for limiting swinging movement of the door, which means eliminates the necessity of providing the usual door check. A plurality of rubber buttons, such as the one shown at 27, engage a shoulder 28 on the door pillar 20 20 to check swinging movement of the door.

Although specific embodiments of the invention have been illustrated and described, it will be understood that various changes may be made within the scope of the appended claims without departing from the spirit of the invention, and such changes are contemplated.

What is claimed is:

1. A concealed hinge for supporting a door from a door pillar in an automobile body having an inclined wall, said hinge comprising a plate member for attachment to the pillar, a pintle carried by said plate member disposed at an angle to the vertical as viewed in a transverse section through said wall, said plate member also supporting said pintle with its axis at an angle to the vertical as viewed in side elevation, an arm member connected to said pintle and adapted for attachment to a door, the axis of said pintle being inclined with respect to the adjacent edge of the door to the extent that said door swings through a substantially horizontal arc during opening and closing movements thereof.

2. A concealed hinge for supporting a door from a door pillar in an automobile body having an inclined wall, said hinge comprising a plate member for attachment to the pillar, a pintle carried by said plate member disposed at an angle to the vertical as viewed in a transverse section through said wall, said plate member also supporting said pintle with its axis at an angle to the vertical as viewed in side elevation, an arm member connected to said pintle and adapted for attachment to a door, the axis of said pintle being inclined with respect to the adjacent edge of the door to the extent that said door swings through a substantially horizontal arc during opening and closing movements thereof, said arc departing from the horizontal only in an amount enabling gravity to bias movement of the door toward a closed position.

3. A concealed hinge adapted to support a curved door on a curved automobile door pillar comprising a hinge plate having hinge pin receiving sockets formed in one edge thereof and adapted for mounting on the door pillar in such manner that the axis of said sockets inclines inwardly of the automobile body and also rearwardly thereof with respect to the adjacent door 70 edge, a hinge pin, a gooseneck hinge means of generally U shape having hinge pin receiving sockets along one edge thereof for attachment to the first named sockets by said hinge pin, the U shape of said gooseneck member varying 75

in length of its branch and in divergence from top to bottom thereof by an amount sufficient to substantially compensate the inclination of said hinge pin whereby a door carried by said gooseneck hinge means swings through a substantially horizontal arc.

4. Means adapted to support the door of an automobile body curved in transverse section comprising a concealed hinge, said concealed hinge comprising a hinge plate, a gooseneck type hinge member of substantial curvature con-

nected directly to said hinge plate, the axis of the connection being at an inclination to the vertical as required by the curvature of the automobile body, said hinge member varying the extent of its curvature from top to bottom there-
in an amount sufficient to substantially com-
pensate the inclination of said axis whereby a door carried by said hinge member swings through a substantially horizontal arc.

EARL E. HOWE.
